(57) **CLAIM**

The ornamental design for a door bin for a refrigerator, as shown and described.

DESCRIPTION

FIG. 1 is a perspective view of a door bin for a refrigerator showing our new design in use condition;

FIG. 2 is an upper right perspective view of the door bin for a refrigerator;

FIG. 3 is a front elevational view thereof;

FIG. 4 is a top plan view thereof;

FIG. 5 is a right side elevational view thereof;

FIG. 6 is a left side elevational view thereof;

FIG. 7 is a rear elevational view thereof; and,

FIG. 8 is a bottom plan view thereof.

The broken lines showing a refrigerator cabinet, a shelving system in the refrigerator cabinet, refrigerator doors, door bin supports and crisper pans in FIG. 1 are for illustrative purposes only and form no part of the claimed invention.
